UNITED STATES PATENT OFFICE.

JOHN MANNING VAN HEUSEN, OF JAMAICA PLAIN, MASSACHUSETTS, ASSIGNOR TO VAN HEUSEN PRODUCTS, INC., A CORPORATION OF DELAWARE.

COLLAR.

Application filed November 16, 1921. Serial No. 515,609.

To all whom it may concern:

Be it known that I, JOHN MANNING VAN HEUSEN, a citizen of the United States of America, residing at Jamaica Plain, in the 5 county of Suffolk, State of Massachusetts, have invented certain new and useful Improvements in Collars; and I do hereby declare the following to be a full, clear, and exact description of the invention, such as 10 will enable others skilled in the art to which it appertains to make and use the same.

This invention relates to improvements in collars and includes improvements both in stand-up collars and in folding or turn-down collars.

According to the present invention, either the collar as a whole, or the folding portion or neck-band portion of the collar, or both, is or are made of separate pieces of fabric 20 secured together by an intermediate binding layer into what is in effect an integral composite fabric.

The ordinary built-up collar, built up of 25 separate pieces of single ply fabric, has the objection, among others, of presenting a flimsy appearance. The collar of the present invention, although built up of separate pieces of fabric, which may be single ply fabric, is nevertheless free from the appearance 30 of flimsiness and the tendency of the collar to wrinkle, above mentioned.

According to the present invention, I take two or more pieces of fabric and secure 35 them together by means of an intermediate cementing or binding medium that is waterproof or water insoluble, and which does not affect in any objectionable way the outside appearance of the fabric, but which nevertheless combines the different layers 40 of fabric together into a composite integral whole.

According to one embodiment of the invention, the collar is built up of different 45 pieces of fabric having a size and shape approximately that of the collar and with their edges turned in so that they can be secured together by stitching or otherwise. Instead, however, of securing these separate pieces of fabric together merely by stitching at their edges, I secure them together throughout their common widths, except at the fold line, and I leave them unsecured 50 at the fold line so that the collar will naturally fold at that point.

According to another embodiment of the

invention, I make a built-up collar with separate neck band and folding or turn-down portion united together at the upper edge of the neck band and I make the folding portion or the neck band, or both, of 60 separate pieces of fabric which are secured together by an intermediate binding layer in a manner similar to that above described. In this case, the neck band or the folding portion, or both, will be given added 65 strength and stiffness and will present more the appearance of a starched collar.

The present invention may, from one standpoint, be considered to involve the building up of a collar in such a way that 70 it presents much the appearance of a permanently starched or stiffened collar, due to the stiffening effect of the separate pieces of fabric upon each other when combined together by the cementing agent in the manner described.

The cementing agent for securing the different layers or plies of fabric together is capable of variation. Agents such as 80 cellulose binding materials can be used. For example, solutions of cellulose derivatives such as cellulose nitrate in suitable solvents, or solutions of cellulose in cellulose solvents such as cuprammonium solutions, or solution of viscose, can be used.

The binding material can be applied in different ways. The separate pieces of fabric may thus for example, be folded in folding machines in much the same manner as in the present collar manufacture, and the 90 separate pieces of the fabric, with their edges turned in, can then be coated with the adhesive material and treated to convert the layer of adhesive into a permanent bond. The fabric can similarly be coated 95 before the edge is turned so that the turned in edge will similarly be secured in place.

After the fabric has been coated, and either before or after the collar has been built up therefrom, the coating can be modified to convert it into a form better adapted for securing the layers of fabric together. In the case of a solution of a cellulose derivative in an organic solvent, the solvent may be partly evaporated before the layers 100 of the fabric are secured together. In other cases, the pieces of fabric may be put together and pressed in a heated press to modify or change the binding material and 105 convert it into its final form. Whatever the 110

particular procedure adapted for applying the binding material to the fabric or for uniting the layers of fabric together, the result will be a built-up collar which, in part or in whole, has the different pieces of the fabric secured together by what may be considered a common binding agent, that is, a binding agent which causes the separate pieces of the fabric to be united to each other into a composite multiple ply fabric, so that the different layers or plies of the fabric will be considerably increased in their stiffness, except at the fold line of the collar.

Instead of using single ply fabric, a somewhat heavier fabric, such as a lightweight two-ply fabric may be used in building up the collars, or in building up parts of them. In such cases, the binding agent may be permitted to penetrate to a greater depth in the two-ply fabric without appearing on the outside of the collar.

Instead of applying a separate adhesive material, the surfaces of the fabric may themselves be acted upon by chemicals so as to give them a sufficient degree of adhesiveness, and the layers so treated may then be secured together, making use of the integral binding agent formed from one or more of the layers of fabric themselves. Again, three separate pieces or plies of fabric may be used and only the inner layer or ply coated with the adhesive or treated to give it an adhesive surface, and the two outer layers can then be secured to this inner layer by means of its adhesive surfaces.

The invention will be further described in connection with the accompanying drawings illustrative of certain embodiments thereof, in which—

Fig. 1 shows in perspective a completed collar embodying the invention.

Fig. 2 shows the collar unfolded.

Fig. 3 is a sectional view of the collar.

Fig. 4 is a sectional view of a modified construction, and

Fig. 5 is a sectional view of a stand-up collar embodying the invention.

The collar of Figs. 1, 2 and 3 is a folding collar made up a neck band portion 1 and folding or turn-down portion 2 with the usual button-holes 3 and 4. The collar as shown, is made up of two separate pieces of thin fabric secured to each other except at the fold line 10. The folding portion of the collar is thus made up of an inner layer 5 and an outer layer 7, secured together by a layer of binding material 12. The neck band portion is similarly made up of an outer layer 6 and an inner layer 8, united to each other by a layer of binding material 12. The edges of the collar are turned in and may be stitched as indicated at 9. At the fold line of the collar, indicated at 10, the binding material 12 is omitted so that

the outer and inner pieces of fabric are not secured together at this point. The fold line is, moreover, made curvilinear as illustrated in order that the collar when folded may have a proper shape.

In building up the collar of Figs. 1 to 3, either one or both of the two separate pieces of fabric may have the layer of the binding material 12 applied thereto either before or after the edges have been turned. If applied before the edges are turned, the turned edges will be held in place by the binding material. The binding material is applied everywhere except at the fold line 10 where it is omitted. The two pieces of the fabric are then placed together and treated, for example, by heat and pressure to cause the cementing material to be converted into its final form and thereby secure the separate layers of fabric together. For example, if the cementing solution is a solution of viscose, this may be treated by heat and pressure to convert the viscose into the form of regenerated cellulose as the binding agent. Solutions of cellulose in other cellulose solvents such as cuprammonium solutions may be similarly treated to convert the cellulose or cellulose compounds into their final stable form such that the layers of fabric will be intimately secured together by the binding agent formed in this way.

In Fig. 4, the collar is a built-up collar in which the neck band and folding portion are secured together at the top of the neck band as by one or more rows of stitches 11. Otherwise, the collar may be built up and secured together in much the same manner as above described in connection with Figs. 1 to 3. Similar or corresponding parts of the collar of Fig. 4 are indicated by the same reference numerals as in Fig. 3, but with the suffix "a" appended thereto. The neck band portion is thus made up of separate pieces of fabric 6^a and 8^a, and in the form illustrated in Fig. 4 these separate pieces are not secured together by an intermediate layer of the binding material but are left separate and unattached as shown. The folding portion is similarly built up but it will be noted that the layers 5^a and 7^a thereof are secured together by an intermediate layer of the binding material 12^a.

In Fig. 5 the collar is a stand-up collar made up of three separate layers or plies of fabric. The outer layers are indicated at 13 and 14 respectively, the inner layer at 16. The inner layer is secured to the outer layers by a suitable cementing material, of which two layers are indicated at 17 and 18 respectively. The collar may be built up in much the same manner as above described, and the collar may be finished by stitching at the edges to give it the customary appearance of a stand-up collar.

According to the preferred construction

- in stand-up collars as illustrated in Fig. 5, the inner layer 16 does not extend the full width of the collar but is terminated at a short distance from the edges thereof. It will be noted that by means of this construction the outer layers 13 and 14 are extended beyond the inner layers 16 and form an open or divided edge. These extensions may be turned in against each other and secured with stitches to form the edge binding of the collar. The bound edges of a collar constructed in this way are of substantially the same thickness as the main portion of the collar and do not form objectionable ridges or welts at the edge portions thereof.
- The present invention is applicable to collars of various styles and fabrics and collars may be made which have an outer fabric (where the collar is exposed to view) which presents the same or substantially the same appearance as the ordinary starched collars, that is, the binding material may be of such a character that it does not penetrate to the outside of the fabric but merely is secured to the inside or penetrates the fabric only to a degree such that it does not objectionably modify the appearance of the outside of the collar.
- I claim—
1. An article of wearing apparel made in whole or in part of separate layers or plies of fabric secured together by an intermediate layer or layers of binding material, at least two layers or plies of fabric extending beyond the main united portion of the fabric, said layers being untreated with the binding material, and turned in and secured to form the edge binding.
  2. An article of wearing apparel made in whole or in part of separate layers or plies of fabric, secured together by an intermediate layer or layers of binding material, the outer layers or plies of fabric extending beyond the inner layer or layers and forming a divided edge which is turned in and stitched to form the edge binding.
  3. A folding or turn-down collar made in whole or in part of separate layers or plies of fabric secured together by an intermediate layer or layers of binding material, at least two of said layers being separate and unattached at the edge portions of the collar, and said unattached layers being turned in and secured to form the edge binding.
  4. A folding or turn-down collar having both its neckband portion and turn-down portion made of separate layers or plies of fabric secured together by an intermediate layer or layers of binding material, at least two of the layers or plies at the edges of the collar being separate and unattached, and the said layers being turned and secured to form the edge binding.
  5. An article of wearing apparel made of separate layers or plies of fabric secured together by an intermediate layer or layers of binding material, the said layer or layers of binding material being omitted along a narrow zone to form a portion of increased flexibility along which the article is adapted to fold.
  6. A folding collar made of separate layers or plies of fabric forming both the neckband and folding portions of the collar, said layers or plies being secured together by an intermediate layer or layers of binding materials except at the fold line of the collar.

In testimony whereof I affix my signature.

JOHN MANNING VAN HEUSEN.
